CLAIM

The ornamental design for a spike transfer housing for use in peritoneal dialysis or the like, as shown.

DESCRIPTION

FIG. 1 is a perspective view of a spike transfer housing for use in peritoneal dialysis or the like showing our new design;

FIG. 2 is a top plan view thereof;

FIG. 3 is a right side elevational view thereof;

FIG. 4 is a bottom plan view thereof;

FIG. 5 is a front end elevational view thereof; and

FIG. 6 is a rear end elevational view thereof.

FIG. 1

FIG. 2

FIG. 3

FIG. 4

FIG. 5

FIG. 6
